UNITED STATES PATENT OFFICE.

GRACE S. MORAHAN, OF SAG HARBOR, NEW YORK.

DESIGN FOR A DOLL.

Application filed June 28, 1928. Serial No. 27,312. Term of patent 3½ years.

To all whom it may concern:

Be it known that I, GRACE S. MORAHAN, a citizen of the United States, residing at Sag Harbor, in the county of Suffolk and State of New York, have invented a new, original, and ornamental Design for a Doll, of which the following is a specification, reference being had to the accompanying drawings, forming a part thereof.

In the drawings, Fig. 1 is a side and Fig. 2 is a front view of a doll embodying my design.

I claim:

The ornamental design for a doll, as shown.

GRACE S. MORAHAN.
